(57) **CLAIM**

The ornamental design for bypass ring for water filtration modules, as shown and described.

DESCRIPTION

FIG. 1 is a top perspective view of a first embodiment of the bypass ring according to the invention;

FIG. 2 is a side view of the bypass ring as shown in FIG. 1; FIG. 3 is a top perspective view of a second embodiment of the bypass ring according to the invention; and, FIG. 4 is a side view of the bypass ring as shown in FIG. 3.
